CLAIR H. BRASSTED, OF CLEVELAND, OHIO, ASSIGNOR TO THE LUDLOW TYPOGRAPH COMPANY, OF CLEVELAND, OHIO, A CORPORATION OF MAINE.

COMPOSING MECHANISM FOR TYPOGRAPHS.

1,091,477.

Specification of Letters Patent. Patented Mar. 31, 1914.

Application filed September 17, 1910, Serial No. 582,454. Renewed June 3, 1912. Serial No. 701,434.

To all whom it may concern:

Be it known that I, CLAIR H. BRASSTED, a citizen of the United States, and a resident of Cleveland, county of Cuyahoga, and State of Ohio, have invented a new and useful Improvement in Composing Mechanism for Typographs, of which the following is a specification, the principle of the invention being herein explained and the best mode in which I have contemplated applying that principle, so as to distinguish it from other inventions.

The improvements comprehended in the present invention relate in general to the Ludlow typograph, the characteristic features of which will be found explained in United States Letters Patent No. 856,531, dated June 11, 1907. In such Ludlow typograph, the means for casting the type line, or slug, comprise a plurality of matrix bars movably resting upon a suitable support which is provided with a transverse casting slot over which such bars are thus adapted to be distributed so as to variously "compose", or aline, the duplicate series of matrices on their under edges.

The present improvements have as their object the provision of means for handling bars in such typograph, whereby they may be thus distributed and subsequently collected with greater facility and increased rapidity.

To the accomplishment of these and related objects said invention, then, consists of the means hereinafter fully described and particularly pointed out in the claims.

The annexed drawings and the following description set forth in detail certain mechanism embodying the invention, such description closed means constituting, however, but one of various mechanical forms in which the principle of the invention may be used.

In said annexed drawings: Figure 1 is a plan view of my improved mechanism and more particularly of the matrix bar distributing and collecting device which forms a feature of such mechanism; Fig. 2 is a side

elevation of such device, as viewed from the left in Fig. 1; Fig. 3 is a sectional view thereof taken on the line 3—3, Figs. 1 and 2; and Fig. 4 is a plan view of the aforesaid mechanism on a smaller scale, together with a more complete representation of the composer frame and other parts of the typograph accessory to said mechanism.

The general composing mechanism to which the present improvements attach comprises in effect an open frame D of general rectangular form (Fig. 4), that is slidably or otherwise mounted upon the bed A of the machine, so as to be movable across the matrix bars C, when the latter are disposed in the trough a' in such bed provided for their reception. This frame typifies in a general way any form of coöperating means adapted to secure the bars in varied longitudinal position in such trough with selected matrices on their under faces located over the casting slot a in the bottom of such trough.

The casting box or mold B' is adapted to fit snugly in such slot and its upper face then lies flush with the bottom of the trough, so that the movement of the bars thereacross is in no way interfered with. The mold is, of course, formed with an opening or slot b' in which the slug is actually cast and it is rather over this opening, than over the general opening in the bottom of the trough, that the matrices on the bars require to be assembled. The general supporting frame for the bed plate or table A, that thus serves as a support for the matrix bars, is not illustrated; but such frame it may be remarked is utilized to support not only the casting mold, but also the other parts of the casting mechanism required for the forming of slugs or lines-of-type in such mold, as need not be further explained.

The matrix bars C are made in general of the laterally tapered form shown in Fig. 1, and are arranged in the trough a' with their tapered ends alternating with the thick ends, whereby the respective bars are maintained

in a line substantially parallel with the walls bounding the trough, whatever variations may be made in the longitudinal position of any individual bar in such trough. The 5 matrices c are struck in or otherwise formed on the lower edge of the bar, regarding the latter as it rests in the trough (Fig. 3). Although adjacent bars will thus be seen to bear similar series of matrices, the order of 10 such matrices will obviously be reversed. In the upper edges of the bars transverse grooves c' are provided corresponding in position with such matrices, and, in connection with the grooves, a series of characters c^2 that likewise correspond with such matrices, although not necessarily placed directly thereover. It may be explained that 15 the foregoing details of construction are not a part of the present invention and are here described only so far as is necessary to an understanding of the latter. Such grooves c' in the upper edge of the bar are adapted for engagement with the splines f^3 on the under sides of two teeth F of the composer 20 frame located on either side of the central line of such frame. Such two centrally located teeth are part of a series of equidistantly spaced teeth that extend inwardly from the rear side of such frame in a trans- 25 verse direction with respect to the matrix bars, or in other words, parallel with the casting slot b^2 in the mold. There are as many of these teeth as there are matrices upon the respective matrix bars carrying 30 the normal font, the disposition of the teeth being such that when the centrally mounted pin c^4 on any bar is inserted in the slot f between the appropriate teeth, the desired matrix in the under side of such bar will 35 be positioned directly over the opening in the mold. To indicate which slot is to be selected to thus bring any desired matrix over the mold, an index plate F' , that for 40 constructional reasons is made in two sections as shown in Fig. 3, is disposed over the teeth F of the frame. Such plate is provided with a double series of designating characters f^2 , one of which series is adapted for 45 use with matrix bars having their thick 50 ends disposed toward the right end of the trough, the other for use with the bars which have their thick ends disposed toward the left of such trough. By detachably securing such index plate to the composer frame, 55 as by screws f^3 , it will be obvious by simply interchanging one plate with another the machine may be adapted for use with an entirely different set of bars on short notice; in other words, it would merely require the 60 substitution of a set of bars bearing matrices for German type, and a corresponding exchange of index plates, to adapt the machine for German composition.

Longitudinally of the frame D along its

front side is mounted a rod or shaft d preferably in standards d' , one at each end, and on this shaft is in turn mounted, so as to be 65 slideable therealong, and also rotatable about the same as an axis, a handled member E constituting the distributing and collecting 70 device of present interest. This device, as clearly shown in Figs. 1, 2 and 3, consists simply of a base plate e that is thus secured to the shaft in question and is formed with a slot e' at right angles to such shaft 75 and of a width sufficient to accommodate in a line the pins c^4 upon the several bars C . Such slot e' is preferably beveled on the under side of the plate, so that as the latter is depressed over the bars, the pins will be 80 readily guided into the slot. It will be understood, of course, that the pins will be brought into a semblance of alignment, before they are thus engaged by the slot, by sweeping the bars together either by engagement of one edge or the other of the handled member with the pins, or in some other way.

The handle e^2 , provided for manipulating member E , is preferably rectangularly 90 disposed with reference thereto, or in other words it is in line with and in a plane above the shaft d , as this presents it in most convenient position for moving the member along the shaft and about the same, it being designed that such handle be grasped in the right hand of the operator. This position of the handle also has regard to the location of the mechanism for releasing successive bars from the slot in the member, it 95 being designed that the actuating lever e^3 of such mechanism be operated by pressure thereagainst with the thumb of the same hand that grasps the handle. Such lever is pivotal about a pin e^4 on the upper face of 100 the plate forming the member's base, and is normally held in the position shown in full lines by a spring e^5 pressing thereagainst, although it may be pressed inwardly into the position indicated in dotted outline. 105 Pivotally attached to the forward end of said actuating lever, one on each side of its pivotal axis, are two fingers e^6 , e^7 , the general form and disposition of which are shown in Fig. 1. Such fingers are connected by a tension spring e^8 that serves to hold them in contact with an interposed stud e^9 , also mounted on the upper face of the base plate e . As a result of the foregoing construction the inward actuation of the lever 110 e^3 acts to withdraw the foremost of said fingers and at the same time insert the inner finger across the line of the pin-retaining slot e' in said base. Such first finger's tip is so disposed as to serve in its normal position as a closure for the outer end of said slot, while the inner finger is disposed so as to be inserted, upon the movement just de-

scribed, in the rear of the first pin behind such first finger's tip in such slot. Said second finger not only is moved across the slot, but also given a slight forward movement sufficient to exert a pressure against the pin, the result of which is the discharge of the latter from the slot.

The matrix bar it will be understood is not transversely moved but rather the member 10 E together with the entire composer frame D, so that such member is retracted sufficient to allow the pin to escape from the slot e' and the teeth of the frame D advanced sufficiently to pick up or engage such pin in 15 a selected slot f between teeth F. Immediately upon the release of the actuating lever of the discharging mechanism, the fingers resume the position illustrated in full lines in Fig. 1, preventing the further retraction 20 of the member and the discharge of another bar until the lever is again actuated. To still further assist in the selection of the desired composer teeth F between which to thus engage the pins on successive matrix 25 bars, the member is provided with a finder E' adapted to coöperate with the index plate F' disposed, as previously described, over the forward ends of such teeth. This finder has an opening e¹⁰ of sufficient longitudinal 30 extent to include both rows of characters f² on the index plate and just wide enough to allow the pair in alinement with the pin-engaging slot e' of the member to appear.

The general operation of my improved 35 composing mechanism has been explained in connection with the foregoing description of its construction sufficiently to require but little further comment. The operator simply grasps the handle e² of the composing 40 device E with the parts in the position shown in Fig. 1, wherein such device is in engagement with the body of bars, and then moves such body of bars longitudinally of the trough until the finder E' is brought 45 over the desired character on the index plate. It will, of course, be necessary for the operator to remember to which row of characters on the plate the characters, or 50 matrices, on his outermost bar correspond. The proper location of such matrix bar having 55 been thus determined, a simple pressure of the thumb upon the actuating lever e³ will release such bar and simultaneously advance the composer frame to engage the same, each successive operation of said lever effecting a shift equal to the width of a bar. This operation is then repeated with the 60 next matrix bar and so on until the entire body has been properly distributed to compose the desired matrix over the casting slot in the mold. The bars being thus distributed, they are locked in place by suitable means (not shown) and a slug then cast in the mold slot b² so as to take the impression

from the composite matrix provided. To 65 re-assemble the bars in a body, such as that in which they appear in Fig. 1, the composing member is tilted upwardly, the frame returned to its initial position in which the bars are uncovered, or in other words, left 70 entirely free from the teeth of the frame, then the member is lowered and by a sweeping movement the bars are brought together in a body with their pins in alinement and adapted to be engaged in the slot in the 75 member ready to be again distributed to compose another matrix.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the class described, the combination of a suitable support, a plurality of matrix bars movable thereon, a member movable longitudinally of said bars 90 and adapted to engage therewith to bring successive bars in desired position with relation to a fixed transverse line, and means directly coöoperative with said bars to shift said member and bars relatively to each 95 other in a direction transverse of the latter.

2. In mechanism of the class described, the combination of a suitable support, a plurality of matrix bars movable thereon, a member movable both longitudinally and transversely of said bars and adapted to engage therewith, whereby successive bars may be brought and left in desired position with reference to a fixed transverse line, and means borne by said member and adapted to 100 coöperate directly with said bars to shift the former in a direction transverse of the latter.

3. In mechanism of the class described, the combination of a suitable support, a plurality of matrix bars movable thereon, a member movable longitudinally of said bars and adapted to engage therewith to bring successive bars in desired position with relation to a fixed transverse line; means directly coöoperative with said bars to shift 110 said member and bars relatively to each other in a direction transverse of the latter so as to release successive bars, and means adapted to secure a bar in its selected position upon said bar being thus released.

4. In mechanism of the class described, the combination of a suitable support, a plurality of matrix bars movable thereon, a member movable both longitudinally and transversely of said bars and adapted to engage therewith, whereby successive bars may be brought and left in desired position with reference to a fixed transverse line, means

- borne by said member and adapted to co-operate directly with successive bars to shift the former in a direction transverse of the latter so as to release successive bars, and 5 means adapted to secure a bar in its selected position upon said bar being thus released.
5. In mechanism of the class described, the combination of a plurality of matrix bars supported so as to be longitudinally 10 movable; a member movable longitudinally of said bars and adapted to engage a number thereof to move the same; and means carried by said member and directly coöperative with said bars to shift said member and 15 bars relatively to each other in a direction transverse of the latter.
6. In mechanism of the class described, the combination of a plurality of matrix bars supported so as to be longitudinally 20 movable; a member movable longitudinally of said bars and adapted to engage a number thereof to move the same; and means carried by said member and directly coöperative with said bars to shift said member and 25 bars relatively to each other in a direction transverse of the latter, each successive operation of said means effecting a shift equal to the width of a bar.
7. In mechanism of the class described, 30 the combination of a plurality of matrix bars supported so as to be longitudinally movable; a member movable both in the same direction as said bars and in a transverse direction thereof, said member being adapted to engage a number of said bars to 35 longitudinally move the same; and means carried by said member and adapted to co-operate directly with said bars to shift said member transversely thereof.
- 40 8. In mechanism of the class described, the combination of a plurality of matrix bars supported so as to be longitudinally movable; a member movable both in the same direction as said bars and in a transverse direction thereof, said member being adapted to engage a number of said bars to 45 longitudinally move the same; and means carried by said member and adapted to co-operate directly with said bars to shift said member transversely thereof, each successive operation of said means effecting a shift of said member equal to the width of a bar.
- 50 9. In mechanism of the class described, the combination of a plurality of matrix bars supported so as to be longitudinally movable; a rod extending parallel with the direction of movement of said bars; a member adapted to engage a number of said bars, said member being movable transversely of said rod into and out of engagement with said bars and also along the same to longitudinally move said bars when in engagement therewith; and means directly coöperative with said bars to shift said member equal to the width of a bar.
- 55 10. In mechanism of the class described, the combination of a plurality of matrix bars supported so as to be longitudinally movable; a rod extending parallel with the direction of movement of said bars; a member adapted to engage a number of said bars, said member being movable transversely of said rod into and out of engagement with said bars and also along the same to longitudinally move said bars when in engagement therewith; and means directly coöperative with said bars to shift said member equal to the width of a bar.
- 60 11. In mechanism of the class described, the combination of a plurality of matrix bars supported so as to be longitudinally movable; a rod extending parallel with the direction of movement of said bars; a member adapted to engage a number of said bars, said member being movable transversely of said rod into and out of engagement with said bars and also along the same to longitudinally move said bars when in engagement therewith; and means directly coöperative with said bars to shift said member equal to the width of a bar.
- 65 12. In mechanism of the class described, the combination of a plurality of matrix bars supported so as to be longitudinally movable; a rod extending parallel with the direction of movement of said bars; a member adapted to engage a number of said bars, said member being oscillatory about said rod into and out of engagement with said bars and also movable along said rod to longitudinally move said bars, when in engagement therewith; and means directly coöperative with said bars to shift said rod, and with it said member, transversely of said bars.
- 70 13. In mechanism of the class described, the combination of a suitable support, a plurality of matrix bars movably resting thereon, composer means adapted variously to engage with said bars, means adapted to move said bars longitudinally of said composer means, and other means directly coöperative with said bars to effect engagement between said composer means and bars.
- 75 14. In mechanism of the class described, the combination of a suitable support, a plurality of matrix bars movably resting there-

ber and bars relatively to each other in a direction transverse of the latter.

10. In mechanism of the class described, the combination of a plurality of matrix bars supported so as to be longitudinally movable; a rod extending parallel with the direction of movement of said bars; a member adapted to engage a number of said bars, said member being movable transversely of said rod into and out of engagement with said bars and also along the same to longitudinally move said bars when in engagement therewith; and means carried by said member and adapted to coöperate directly with said bars to shift said member and bars relatively to each other, each successive operation of said means effecting a shift equal to the width of a bar.

11. In mechanism of the class described, the combination of a plurality of matrix bars supported so as to be longitudinally movable; a rod extending parallel with the direction of movement of said bars, said rod being bodily movable in a direction transverse of such matrix bar movement; a member adapted to engage a number of said bars, said member being oscillatory about said rod into and out of engagement with said bars and also movable along said rod to longitudinally move said bars, when in engagement therewith; and means directly coöperative with said bars to shift said rod, and with it said member, transversely of said bars.

12. In mechanism of the class described, the combination of a plurality of matrix bars supported so as to be longitudinally movable; a rod extending parallel with the direction of movement of said bars, said rod being bodily movable in a direction transverse of such matrix bar movement; a member adapted to engage a number of said bars, said member being oscillatory about said rod into and out of engagement with said bars and also movable along said rod to longitudinally move said bars, when in engagement therewith; and means carried by said member and directly coöperative with said bars to shift said rod, and with it said member, transversely of said bars, each operation of said means effecting a shift equal to the width of a bar.

13. In mechanism of the class described, the combination of a suitable support, a plurality of matrix bars movably resting thereon, composer means adapted variously to engage with said bars, means adapted to move said bars longitudinally of said composer means, and other means directly coöperative with said bars to effect engagement between said composer means and bars.

14. In mechanism of the class described, the combination of a suitable support, a plurality of matrix bars movably resting there-

on, composer means movable transversely of said bars and adapted variously to engage therewith, means adapted to move said bars longitudinally of said composer means, and 5 other means adapted to coöperate directly with said bars to shift said composer means transversely thereof.

15. In mechanism of the class described, the combination of a suitable support, a plurality of matrix bars movably resting thereon, composer means adapted variously to engage with said bars, a member movable longitudinally of said bars and adapted to engage therewith to bring successive bars in 15 desired position with respect to said composer means, and means directly coöoperative with said bars to shift said member and composing means relatively to said bars in a direction transverse of the latter.

20. 16. In mechanism of the class described, the combination of a suitable support, a plurality of matrix bars movably resting thereon, composer means movable transversely of said bars and adapted variously to engage therewith, a member movable both longitudinally and transversely of said bars and adapted to engage therewith, whereby successive bars may be brought and left in desired position with respect to said composer 25 means, and means borne by said member and adapted to coöperate directly with said bars to shift said member and composer means in a direction transverse of said bars.

30. 17. In mechanism of the class described, the combination of a substantially horizontal support, a plurality of matrix bars movably resting thereon, an engaging element on each of said bars, a transversely disposed member movable both longitudinally and 35 transversely of said bars and adapted to engage with the elements thereon, and means borne by said member and adapted to coöperate directly with said bars to shift said member across the same.

40. 18. In mechanism of the class described, the combination of a substantially horizontal support, a plurality of matrix bars movably resting thereon, an upwardly extending projection on each of said bars, a transversely disposed member movable both longitudinally and transversely of said bars and adapted to detachably engage with the projections thereon, and means borne by said member and adapted to coöperate with the 45 projections on successive bars to shift said member across the same.

50. 19. In mechanism of the class described, the combination of a substantially horizontal support, a plurality of matrix bars movably resting thereon, an upwardly extending projection on each of said bars, a transversely disposed member movable both longitudinally and transversely of said bars and adapted to detachably engage with the 55 projections on successive bars to shift said member across the same.

60. 20. In mechanism of the class described, the combination of a substantially horizontal support, a plurality of matrix bars movably resting thereon, an upwardly extending projection on each of said bars, a transversely disposed member movable both longitudinally and transversely of said bars and adapted to detachably engage with the 65 projections thereon, and a finger movably mounted on said member and adapted to coöperate with the projection on the outermost bar to transversely shift said member a distance sufficient to release said bar.

70. 21. In mechanism of the class described, the combination of a substantially horizontal support, a plurality of matrix bars movably resting thereon, an upwardly extending projection on each of said bars, a transversely disposed member movable both longitudinally and transversely of said bars and adapted to detachably engage with the projections thereon, and two movable fingers borne by said member, and respectively adapted to coöperate with the projection on the outermost bar, the first to restrain movement of said member transversely of said bars and the second to thus shift said member a distance sufficient to release such outermost bar.

75. 22. In mechanism of the class described, the combination of a substantially horizontal support, a plurality of matrix bars movably resting thereon, an upwardly extending projection on each of said bars, a transversely disposed member movable both longitudinally and transversely of said bars and adapted to detachably engage with the projections thereon, two fingers movably mounted on said member and respectively adapted 80 to coöperate with opposite sides of the projection on the outermost bar, the first to restrain movement of said member transversely of said bars and the second to thus shift said member a distance sufficient to release such outermost bar, and a lever adapted 85 to actuate said fingers.

90. 23. In mechanism of the class described, the combination of a substantially horizontal support, a plurality of matrix bars movably resting thereon, an upwardly extending projection on each of said bars, a transversely disposed member movable both longitudinally and transversely of said bars and adapted to detachably engage with the projections thereon, two fingers movably mounted on said member and respectively adapted 95 to coöperate with opposite sides of the projection on the outermost bar, the first to restrain movement of said member transversely of said bars and the second to thus shift said member a distance sufficient to release such outermost bar, a lever adapted 100 to actuate said fingers, and a spring normally holding said lever with said first finger operative and said second finger inoperative.

105. 24. In mechanism of the class described, the combination of a substantially horizontal support, a plurality of matrix bars movably resting thereon, an upwardly extending projection on each of said bars, and a member movable longitudinally of said bars 110

and having a transverse slot adapted to engage the projections on said bars, such slot being beveled on its under side to facilitate such engagement.

- 5 24. In mechanism of the class described, the combination of a substantially horizontal support, a plurality of matrix bars movably resting thereon, an upwardly extending projection on each of said bars, a rod extending longitudinally of said bars, a member movable along and oscillatory about said rod and having a transverse slot adapted to engage the projections on said bars, such slot being beveled on its under side to facilitate such engagement.

- 10 25. In mechanism of the class described, the combination of a substantially horizontal support, a plurality of matrix bars movably resting thereon, an upwardly extending projection on each of said bars, a transversely disposed member movable longitudinally of said bars and adapted to engage the projections thereon, and a handle on said member disposed in substantial alinement 20 with said member's direction of movement.

- 25 26. In mechanism of the class described, the combination of a substantially horizontal support, a plurality of matrix bars movably resting thereon, an upwardly extending projection on each of said bars, a rod extending longitudinally of said bars, a member movable along and oscillatory about said rod and adapted to engage the projections on said bars, and a handle on said member disposed in substantial alinement 30 with said member's direction of movement and in a plane above its axis of oscillation.

- 35 27. In mechanism of the class described, the combination of a substantially horizontal support, a plurality of matrix bars movably resting thereon, an upwardly extending projection on each of said bars, a frame movable across said bars and having transversely disposed teeth along one side adapted 40 to engage such projections, a rod longitudinally mounted on the other side of said frame, a member movable along and oscillatory about said rod and having a transverse slot adapted to engage the projections 45 on said bars, and means borne by said member and adapted to coöperate with the projections on successive bars to shift said member and thereby said frame across the same.

- 50 28. In mechanism of the class described, the combination of a substantially horizontal support, a plurality of matrix bars movably resting thereon, an upwardly extending projection on each of said bars, a frame movable across said bars and having transversely disposed teeth along one side adapted 55 to engage such projections, a rod longitudinally mounted on the other side of said frame, a member movable along and oscillatory about said rod and having a trans-

verse slot adapted to engage the projections 65 on said bars, and a movably mounted finger on said member adapted to coöperate with the projection on the outermost bar to transversely shift said member, and thereby said frame, a distance sufficient to release 70 said bar from the former and engage the same by the teeth on the latter.

29. In mechanism of the class described, the combination of a substantially horizontal support, a plurality of matrix bars movably resting thereon, an upwardly extending projection on each of said bars, a frame 75 movable across said bars and having transversely disposed teeth along one side adapted to engage such projections, a rod longitudinally mounted on the other side of said frame, a member movable along and oscillatory about said rod and having a transverse slot adapted to engage the projections 80 on said bars, and two fingers movably mounted on said member and respectively adapted to coöperate with the outermost bar, the first to restrain movement of said member transversely of said bars and the second to thus shift said member, and thereby said 85 frame, a distance sufficient to release said bar from the former and engage the same by the teeth on the latter.

30. In mechanism of the class described, the combination of a substantially horizontal support, a plurality of matrix bars movably resting thereon, an upwardly extending projection on each of said bars, a frame 90 movable across said bars and having transversely disposed teeth along one side adapted to engage such projections, a rod longitudinally mounted on the other side of said frame, a member movable along and oscillatory about said rod and having a transverse slot adapted to engage the projections 95 on said bars, and two fingers movably mounted on said member and respectively adapted to coöperate with the outermost bar, the first to restrain movement of said member transversely of said bars and the second to thus shift said member, and thereby said frame, a distance sufficient to release said bar from the former and engage the same by the teeth on the latter. 100

31. In mechanism of the class described, the combination of a substantially horizontal support, a plurality of matrix bars movably resting thereon, an upwardly extending 105 projection on each of said bars, a frame movable across said bars and having transversely disposed teeth along one side adapted to engage such projections, a rod longitudinally mounted on the other side of said frame, a member movable along and oscillatory about said rod and having a transverse slot adapted to engage the projections 110 on said bars, and two fingers movably mounted on said member and respectively adapted to coöperate with the outermost bar, the first to restrain movement of said member transversely of said bars and the second to thus shift said member, and thereby said frame, a distance sufficient to release said bar from the former and engage the same by the teeth on the latter, and a lever on said member 115 adapted to actuate said fingers alternately.

32. In mechanism of the class described, the combination of a substantially horizontal support, a plurality of matrix bars movably resting thereon, an upwardly extending 120 projection on each of said bars, a frame movable across said bars and having transversely disposed teeth along one side adapted to engage such projections, a rod longitudinally mounted on the other side of said frame, a member movable along and oscillatory about said rod and having a transverse slot adapted to engage the projections 125 on said bars, and two fingers movably mounted on said member and respectively adapted to coöperate with the outermost bar, the first to restrain movement of said member transversely of said bars and the second to thus shift said member, and thereby said frame, a distance sufficient to release said bar from the former and engage the same by the teeth on the latter.

on said bars, two fingers movably mounted on said member and respectively adapted to coöperate with opposite sides of the projection on the outermost of said bars, the 5 first to restrain movement of said member transversely of said bars and the second to thus shift said member, and thereby said frame, a distance sufficient to release said bar from the former and engage the same 10 by the teeth on the latter, a lever on said

member adapted to actuate said fingers, and a spring normally holding said lever with said first finger operative and said second finger inoperative.

Signed by me this 12th day of September 15
1910.

CLAIR H. BRASTED.
